(57) **CLAIM**

The ornamental design for a bumper for vehicle, as shown and described.

DESCRIPTION

FIG. 1 is a top right perspective view of a bumper for vehicle showing our new design.

FIG. 2 is a front view thereof.

FIG. 3 is a left side view thereof.

FIG. 4 is a right side view thereof; and,

FIG. 5 is a bottom view thereof.

The broken lines and de-emphasized portions shown inside the broken lines in the drawings illustrate portions of the bumper for vehicle that form no part of the claimed design.

1 Claim, 3 Drawing Sheets(56)
